HAIR-DRESSING TOOL

Herman C. Schlicker, Brooklyn, N. Y.

Application March 22, 1938, Serial No. 197,831

8 Claims. (Cl. 132—33)

The present invention relates to hair-dressing tools, and is more particularly directed toward a device for use in curling the hair.

The present invention contemplates a mandrel 5 about which a tress of hair may be wound, and the association with this mandrel of suitable means for holding a hairpin in such a way that the coil of hair wound on the mandrel may be slid off the mandrel into the hairpin to be retained in wound shape by the mandrel.

According to the present invention the one shank of the hairpin is insertible into the end of the mandrel and is revolvable relative to the mandrel, so that the mandrel or the hairpin may 15 be turned independently of one another. It is also contemplated that the hairpin may be inserted into the mandrel after the winding operation has been completed.

A further object of the invention is to arrange 20 the parts so that the hairpin is spread when the shank is inserted into the mandrel and is automatically shifted to a position to provide a wide opening to receive the wound coil of hair being removed from the mandrel.

Other and further objects of the invention will 25 appear as the description proceeds.

The accompanying drawing shows, for purposes of illustrating the present invention, two of the many embodiments in which the invention 30 may take form, it being understood that the drawing is illustrative of the invention rather than limiting the same.

In the drawing:—

Figure 1 is a side elevational view of a hair-dressing tool embodying a comb in addition to the mandrel;

Figure 2 is a top plan view of the device of Figure 1;

Figure 3 is an enlarged longitudinal sectional view taken on the line 3—3 of Figure 2;

Figure 3A is an end elevational view of the device taken from the left of Figures 1 and 2;

Figure 4 is a sectional view taken on the line 4—4 of Figure 3;

Figure 5 is a view illustrating the starting of the winding of the coil of hair;

Figure 6 is a view illustrating the coil of hair more completely wound;

Figure 7 is a view illustrating the coil of hair with the hairpin holding it against unwinding; and

Figure 8 is a sectional view through a modified form of construction.

In the form of construction shown in Figures 1—6 of the drawing a single body member 10 is

formed to provide a comb 11 at the right-hand end and a mandrel 12 at the left. This mandrel may be round or flattened as desired; and is of a size on which it is convenient to wind a tress of hair to form a curl.

A suitable clamping member 13 is secured to the body member 10 by a pivot indicated at 14. This clamping member has a finger-piece 15 and a long thin shank 16 adapted to overlie the mandrel as indicated. The clamp is urged to the 10 position shown in the drawing by a coil spring 17.

The outer end of the mandrel is counterbored, as indicated at 18, and the end of the counterbore is closed by a plug 19 apertured as indicated at 20. This aperture is preferably centrally located and is large enough to receive the shank 21 of a hairpin 22. The depth of the counterbore 18 is such that the end of the shank 21 of the hairpin is stopped in such position that loop 23 of the hairpin protrudes a predetermined distance from the end of the mandrel. The end of the mandrel is preferably shaped as indicated in the drawing, and is of such dimension as to swing the exposed shank of the hairpin away from the mandrel. The extent of this swinging 25 or spreading movement is increased by reason of the fact that the diameter of the counterbore 18 is substantially larger than the size of the hole 20 through which the shank of the hairpin has been inserted, so that it may be inclined relative 30 to the mandrel axis.

The winding of the tress of hair onto the mandrel is readily accomplished by clamping the ends of the hair onto the mandrel and then turning the mandrel to roll the hair into a coil. The 35 hairpin may then be placed as indicated in Figure 3 of the drawing, and can be turned so as to bring the hairpin to such position as to bring it close to the scalp, so as to grip the hair as near the scalp as possible. Releasing the pressure of 40 the spring operated clamp on the ends of the hair permits one to slide the wound coil off the mandrel and in between the shanks of the hairpin, and further movement pulls the hairpin away from the mandrel causing the hairpin to 45 close down on the wound tress of hair, as indicated in Figure 7.

In the arrangement of Figure 8, the mandrel 25 is in the form of a metal tube, which may be seamless or a piece of rolled sheet metal. The 50 outer end of the mandrel is constricted as indicated at 26 and has an opening 27 for the hairpin. A handle 28, which may include a comb, has a reduced end 29 adapted to be received in the mandrel and suitably secured therein, as by up- 55

setting a part of the mandrel, as indicated at 30. A pin 31 preferably resilient, is secured in the handle and overlies the mandrel as indicated. The ends of the hair are inserted between the pin and the mandrel, and the entire device is used the same as that of Figures 1-8.

The present device forms a very convenient hair-dressing tool in that both the combing and curling operations can be carried out with the same tool, the mandrel forming the handle for the comb and the comb forming the handle for turning the mandrel.

It is obvious that the invention may be embodied in many forms and constructions within the scope of the claims and I wish it to be understood that the particular forms shown are but two of the many forms. Various modifications and changes being possible, I do not otherwise limit myself in any way with respect thereto.

20. What is claimed is:

1. A hair-curling device comprising a manually revolvable mandrel about which a tress of hair may be wound to form a coil, the mandrel having a smooth end and an axially extending opening of a diameter to receive a hairpin shank, a resilient hairpin having one shank rotatably received in the opening so that the hairpin can be turned relative to the mandrel, the end of the mandrel being thicker than the normal spacing 30 of the shanks of the hairpin so that the wall of the mandrel is gripped and the exposed shank is spread away from the mandrel and is adapted to overlie the wound coil of hair when it is slid off the end of the mandrel.

35. 2. A hair-curling device such as claimed in claim 1, wherein the depth of the opening is slightly less than the length of the shank to afford a stop, so that a small portion of the end of the hairpin is exposed for manipulation.

40. 3. A hair-curling device such as claimed in claim 1, wherein the opening has a small diameter at the end of the mandrel and has a larger diameter at its inner end so that the inner end of the inserted shank will be moved off center and the end of the exposed shank moved away from the 45 mandrel.

45. 4. In a hair-curling device, a manually revolvable mandrel about which a tress of hair may be wound to form a coil, the mandrel having an axially extending opening, a plug in the end of the mandrel having an opening substantially

smaller in diameter than the opening in the mandrel, a spring hairpin having a shank insertible through the opening in the plug and into the opening in the mandrel and rotatable in both openings, the hairpin having a loop portion to grip the plug and a shank extending obliquely away from the mandrel, the enclosed shank being automatically held in an inclined position relative to the mandrel axis. 5

5. A hair-dressing tool comprising a body member having comb teeth at one end and a handle end in the form of a mandrel, a clamp pivoted to the mid-portion of the body and having a gripping member overlying the mandrel, and a finger-piece adjacent and generally in the plane 15 of the comb teeth, and a hairpin insertible into the end of the mandrel, the shanks of the hairpin being spread when said shank is inserted into the mandrel, the hairpin being revolvable with respect to the mandrel. 20

6. In a hair-dressing tool, a mandrel about which hair is adapted to be wound to form a coil, the end of the mandrel having an axially disposed opening adapted to receive a shank of a hairpin, the mandrel having a chamber into 25 which the opening communicates, the chamber being of larger diameter than the opening so that the enclosed shank may be held in an inclined position relative to the mandrel axis.

7. In a hair-dressing tool, a mandrel about 30 which hair is adapted to be wound to form a coil, the end of the mandrel having an axially disposed opening adapted to receive a shank of a hairpin, the mandrel having a chamber into which the opening communicates, the chamber 35 being of larger diameter than the opening so that the enclosed shank may be held in an inclined position relative to the mandrel axis and of a depth to limit the extent to which the shank may be inserted, a handle extending from the opposite end of the mandrel, and a hair-clamping device overlying the mandrel. 40

8. A hair-dressing tool comprising a tubular mandrel open at one end and having a small axially disposed opening at the other end adapted to receive the shank of a hairpin, a handle having a reduced end extending into the first end of the mandrel to support the mandrel and form a stop to limit the extent to which said shank may be inserted. 45

DISCLAIMER

2,146,160.—*Herman C. Schlicker, Brooklyn, N. Y. HAIR-DRESSING TOOL. Patent dated February 7, 1939. Disclaimer filed January 4, 1940, by the assignee, Rollocurl Corporation.*

Hereby enters this disclaimer of claims 1, 2, 3, and 6 of said patent.
[Official Gazette January 30, 1940.]

setting a part of the mandrel, as indicated at 30. A pin 31 preferably resilient, is secured in the handle and overlies the mandrel as indicated. The ends of the hair are inserted between the pin and the mandrel, and the entire device is used the same as that of Figures 1-8.

The present device forms a very convenient hair-dressing tool in that both the combing and curling operations can be carried out with the same tool, the mandrel forming the handle for the comb and the comb forming the handle for turning the mandrel.

It is obvious that the invention may be embodied in many forms and constructions within the scope of the claims and I wish it to be understood that the particular forms shown are but two of the many forms. Various modifications and changes being possible, I do not otherwise limit myself in any way with respect thereto.

20. What is claimed is:

1. A hair-curling device comprising a manually revolvable mandrel about which a tress of hair may be wound to form a coil, the mandrel having a smooth end and an axially extending opening of a diameter to receive a hairpin shank, a resilient hairpin having one shank rotatably received in the opening so that the hairpin can be turned relative to the mandrel, the end of the mandrel being thicker than the normal spacing 30 of the shanks of the hairpin so that the wall of the mandrel is gripped and the exposed shank is spread away from the mandrel and is adapted to overlie the wound coil of hair when it is slid off the end of the mandrel.

35. 2. A hair-curling device such as claimed in claim 1, wherein the depth of the opening is slightly less than the length of the shank to afford a stop, so that a small portion of the end of the hairpin is exposed for manipulation.

40. 3. A hair-curling device such as claimed in claim 1, wherein the opening has a small diameter at the end of the mandrel and has a larger diameter at its inner end so that the inner end of the inserted shank will be moved off center and the end of the exposed shank moved away from the 45 mandrel.

45. 4. In a hair-curling device, a manually revolvable mandrel about which a tress of hair may be wound to form a coil, the mandrel having an axially extending opening, a plug in the end of the mandrel having an opening substantially

smaller in diameter than the opening in the mandrel, a spring hairpin having a shank insertible through the opening in the plug and into the opening in the mandrel and rotatable in both openings, the hairpin having a loop portion to grip the plug and a shank extending obliquely away from the mandrel, the enclosed shank being automatically held in an inclined position relative to the mandrel axis. 5

5. A hair-dressing tool comprising a body member having comb teeth at one end and a handle end in the form of a mandrel, a clamp pivoted to the mid-portion of the body and having a gripping member overlying the mandrel, and a finger-piece adjacent and generally in the plane 15 of the comb teeth, and a hairpin insertible into the end of the mandrel, the shanks of the hairpin being spread when said shank is inserted into the mandrel, the hairpin being revolvable with respect to the mandrel. 20

6. In a hair-dressing tool, a mandrel about which hair is adapted to be wound to form a coil, the end of the mandrel having an axially disposed opening adapted to receive a shank of a hairpin, the mandrel having a chamber into 25 which the opening communicates, the chamber being of larger diameter than the opening so that the enclosed shank may be held in an inclined position relative to the mandrel axis.

7. In a hair-dressing tool, a mandrel about 30 which hair is adapted to be wound to form a coil, the end of the mandrel having an axially disposed opening adapted to receive a shank of a hairpin, the mandrel having a chamber into which the opening communicates, the chamber 35 being of larger diameter than the opening so that the enclosed shank may be held in an inclined position relative to the mandrel axis and of a depth to limit the extent to which the shank may be inserted, a handle extending from the opposite end of the mandrel, and a hair-clamping device overlying the mandrel. 40

8. A hair-dressing tool comprising a tubular mandrel open at one end and having a small axially disposed opening at the other end adapted to receive the shank of a hairpin, a handle having a reduced end extending into the first end of the mandrel to support the mandrel and form a stop to limit the extent to which said shank may be inserted. 45
